UNITED STATES PATENT OFFICE

168,197

COMBINED VAPOR DIFFUSER AND ASH TRAY

John Max von Bergen, Scotch Plains, N. J., and
George W. Meek, Pelham, N. Y.

Application May 21, 1951, Serial No. 15,275

Term of patent 7 years

(Cl. D85—2)

To all whom it may concern:

Be it known that we, John Max von Bergen, a citizen of the United States, residing at Scotch Plains, county of Union, State of New Jersey, and George W. Meek, a citizen of the United States, residing at Pelham, county of Westchester, State of New York, have invented a new, original, and ornamental Design for a Combined Vapor Diffuser and Ash Tray, of which the following is a specification, reference being had to the accompanying drawing, forming part thereof, in which:

Fig. 1 is a perspective view of a combined vapor diffuser and ash tray showing our new design with the vapor outlets partially open;

Fig. 2 is a top plan view thereof;

Fig. 3 is a bottom plan view thereof;

Fig. 4 is a side elevational view thereof;

Fig. 5 is a partial vertical cross-sectional view thereof, taken on the line 5—5 as shown in Fig. 2;

Fig. 6 is a partial horizontal cross-sectional view thereof, taken on the line 6—6 as shown in Fig. 4.

In Figs. 1 and 2 the transverse lines in the upper ash tray part have been employed to indicate transparency. In these views it will also be noted that the concentric lines represent concentric grooves in the lower surface of the tray, as seen

in Fig. 5, when viewed through the transparent body thereof.

This application is a continuation-in-part of our co-pending application, Serial No. D-8702, filed March 22, 1950, now abandoned.

We claim:

The ornamental design for a combined vapor diffuser and ash tray, as shown and described.

JOHN MAX VON BERGEN.
GEORGE W. MEEK.
